CLAIM

The ornamental design for a part for vehicles, as shown and described.

DESCRIPTION

1. Part for vehicles

1.1 : Front perspective view

1.2 : Rear perspective view

1.3 : Front

1.4 : Rear view

1.5 : Side view

1.6 : Top

1.7 : Bottom

2.1 : Perspective

2.2 : Rear view

2.3 : Left side view

2.4 : Front

2.5 : Right side view

2.6 : Top

2.7 : Bottom

Portions of vehicle shown in broken lines form no part of the claimed design.

The present design relates to parts for vehicles, as illustrated in the annexed drawings. Design 1: FIG. 1.1 is a front perspective view of part for vehicles of the present design; FIG. 1.2 is a rear perspective view thereof; FIG. 1.3 is a front view thereof; FIG. 1.4 is a rear view thereof; FIG. 1.5 is a side view thereof, the opposite side views being mirror images; FIG. 1.6 is a top view thereof; and FIG. 1.7 is a bottom view thereof. Figures that show the design most sufficiently: front and rear perspective views.
